ATTORNEY.

UNITED STATES PATENT OFFICE.

JAMES THOMPSON, OF BALTIMORE, MARYLAND.

WINDOW.

SPECIFICATION forming part of Letters Patent No. 249,697, dated November 15, 1881.

Application filed October 10, 1881. (No model.)

To all whom it may concern:

Be it known that I, JAMES THOMPSON, of Baltimore city, State of Maryland, have invented certain new and useful Improvements 5 in Windows; and I hereby declare the same to be fully, clearly, and exactly described as follows, reference being had to the accompanying drawings, in which—

Figure 1 is a perspective view, and Fig. 2 a 10 central vertical sectional view, of a window embodying my invention.

My said invention relates to the front or sidewalk windows of stores having stands for the display of wares; and it has for its object to 15 provide a window of that class having a sliding removable stand adapted to be retracted upon suitable guide-rails, and afford facility for arranging the goods upon the stand and give access to the glass for cleaning it.

20 In the drawings, A is the front pane of a sidewalk-window, and B is the platform upon which the goods and wares are arranged for display. It is mounted upon supports *a a*, which are mortised into bars *a'*, in the ends of 25 which latter are pivoted rollers *b*, that run on rails C. The rear *c* of the platform B is, by preference, faced with a mirror, and has a handle, E, whereby the entire device may be retracted within the store to dress the platform 30 or afford access to the window. The part D is glazed, so as to give light to the interior of the store from without, and the top of the frame *f* is beveled, as shown, so as to fit closely against a bead, *e*, on the ceiling of the window-space.

35 The additional advantages of this construction are that it closes the window-space closely, and prevents in summer the entrance of flies

and in winter the condensation and freezing of moisture on the front pane.

The device may readily be applied to the ordinary window-space at a trifling cost, and is 40 a great convenience.

The platform is more tastefully dressed from the front, as is possible with my device, facility is afforded for removing any article which is 45 fancied by a purchaser, and the window-space is practically sealed. The air of the interior being thus cut off from access to the window-space, the condensation of moisture in winter is imperceptible, and the windows are never 50 rendered opaque by ice from condensed moisture.

Having thus described my invention, what I claim is—

1. A shop or store window having a retractible platform mounted upon rollers, in combination with a suitable railway or guide for directing the motion of the platform and guiding it into place, as set forth. 55

2. In combination with the window and rail-way C, the platform mounted upon suitable supports and rollers, and having a backing arranged to close tightly against the ceiling and walls of the window-space, as set forth. 60

3. In combination with the window A and platform B, the supports *a*, rollers *b*, rails C, and backing *c D*, having handle E, and adapted to close the rear of the window-space, as set forth. 65

JAS. THOMPSON.
